JUVENILE VEHICLE WHEEL

Harry Golden, New York, N.Y., assignor to Ideas for
Auto and Bike Specialties, Inc., New York, N.Y.

Filed May 7, 1970, Ser. No. 22,878

Term of patent 14 years

Int. Cl. D12—14

U.S. Cl. D14—30

FIG. 3

FIG. 2

FIG. 1

FIG. 1 is a side elevational view of a juvenile vehicle wheel showing my new design, the opposite side being a mirror image thereof; and

FIG. 2 is an end elevational view thereof; and
FIG. 3 is a sectional view thereof taken along the line 3—3 of FIG. 1.

I claim:

The ornamental design for a juvenile vehicle wheel, as shown and described.
